UNITED STATES PATENT OFFICE.

WILLIAM E. CHOATE, OF HAMILTON, MASSACHUSETTS.

ART OF MANIPULATING TENUOUS METALLIC LAMELLÆ.

1,279,655.

Specification of Letters Patent. Patented Sept. 24, 1918.

Application filed March 24, 1916. Serial No. 86,487.

To all whom it may concern:

Be it known that I, WILLIAM E. CHOATE, a citizen of the United States, and a resident of Hamilton, in the county of Essex and State of Massachusetts, have invented 5 an Improvement in Art of Manipulating Tenuous Metallic Lamellæ, of which the following description, in connection with the accompanying drawings, is a specification, 10 like characters on the drawings representing like parts.

This invention relates to the art of manipulating tenuous metallic lamellæ such as gold leaf and the purpose is to provide methods and equipment for practising them whereby articles may be ornamented, marked or covered with metallic leaf with greater facility than has hitherto been possible and at the same time the highest standard of 20 quality in the work be maintained.

The great thinness of gold leaf (I shall hereafter for convenience refer specifically to gold leaf as typical of similar leaves or foils) renders the use of it a matter of extreme delicacy. Attempts have been made 25 to simplify the operation of applying the leaf by utilizing a backing or mounting during the process of application, which mounting was removed from the finished work. 30 These efforts while making the handling of the leaf easier were found to adversely effect the quality of the work in that the luster or metallic sheen of the metal was lost. The effect of my invention is to preserve the true 35 luster of the beaten gold, while at the same time providing for convenient manipulation of the leaf.

My invention will be best understood by reference to the following description taken 40 in connection with the accompanying drawings, wherein:—

Figures 1, 2 and 3 are views showing successive steps in the preparation of my novel mounted gold leaf such as is used in carrying 45 out my process;

Fig. 4 is a diagrammatic view showing the use of the product referred to in my novel process. It will be understood that the thickness of the various layers is enormously 50 exaggerated;

Fig. 5 is a view showing the final step in marking an article.

In Figs. 1 to 3 I have illustrated a simple method of preparing my novel mounted leaf 55 and have there shown it as made up in the form of a book similar to that commonly

used as a carrier for gold leaf but this form of packaging it is not essential. For the purposes of my invention I mount each leaf of gold on a backing which will not only serve 60 as a carrier therefor but which will act as a burnisher when the leaf is used. This backing may be of any suitable character but desirably I use a thin paper of homogeneous texture or consistency and having a surface 65 of great smoothness so that there are no perceptible asperities or any roughness in the substance of the backing which could be transmitted to the gold. Certain suitable papers are commercially known as "glassine" and "onion skin". The specific steps by which the papers known commercially by these names are manufactured are zealously guarded as trade secrets. The general manner of manufacturing them is known, 70 however, and I briefly explain it here, basing my explanation on the report of a consulting chemist. Glassine paper, otherwise known as pergamyn paper, is paper in which hydration of the cellulose fiber has taken 75 place due to prolonged heating of the fibers in the beating engine or to special and severe conditions of beating and refining. Such hydration and comminution result in the partial coalescence of the cell walls thus 80 forming a more homogeneous and membranous-like sheet than ordinary paper, in which there is simply an interlacing and frictional contact of the fibers. Glassine paper is further characterized by being practically, 85 greaseproof and waterproof and translucent or transparent and by having a glazed or glossy surface, which transparency or glossy finish is brought about by special methods of calendering. Parchment 90 paper, onion skin paper and certain other papers share with glassine to a greater or less degree the properties of exceptional homogeneity and membranous appearance. Parchment paper differs from glassine paper 95 in the kind of fiber used in its manufacture, but principally in that the hydration of the cellulose is effected by use of chemical agents having hydrolytic action on cellulose instead of by mechanical means. Onion skin paper and certain other semi-transparent papers differ from glassine mainly in degree of hydration (which governs homogeneity), in kind of fiber used, in finish, transparency and greaseproofness. These papers are 100 adapted to the purpose in hand because of their substantially amorphous texture with- 110

out palpable fiber or grain throughout their substance and smooth, superficial surface. The use of material of this nature is of utmost importance, the ordinary tissue commonly used in gold leaf books and mountings being entirely inapplicable to the purpose of my invention. A sheet of this paper as 1 (Fig. 1) is laid on a perfectly smooth surface and superficially coated with a suitable unctuous adhesive. For this purpose a hard wax such as paraffin or carnauba wax or a similar cereous substance is adaptable. A piece of wax 2 shown in the drawing mounted in a suitable handle is drawn over the sheet 1 with a gentle even pressure which will cause a thin coating 3 of wax to be applied to the sheet 1. A leaf of gold 4 is laid smoothly on the prepared sheet 1 and a second sheet 1^a like the sheet 1 is laid over the whole (Fig. 2). The second sheet is then in turn treated with wax (Fig. 3) and the pressure incidental to that operation will cause the leaf 4 to adhere to the prepared sheet 1. The sheet 1 with the adhering sheet 4 may now be handled with comparative freedom without danger of breaking or wrinkling the gold. This method facilitates not only the repairing of pinholes or torn places in a leaf of metal by permitting patches to be added, but allows whole additional leaves to be added when a more opaque or heavier thickness of metal is desired inasmuch as no coating has to be added to the exposed face of the leaf and the leaves of gold readily amalgamate or weld cold when pressed together.

I wish to emphasize that according to my invention the leaf is only superficially attached to the sheet 1. Attempts have been made to prepare leaf cohering with a backing by subjecting the leaf and backing to comparatively great pressure, but while an easily handled assemblage resulted the luster of the metal was entirely lost. It appears that the comparative roughness of the paper backing used was transferred to the gold and destroyed its smooth surface. Furthermore, a superficial adherence allows relative movement of the gold and the burnishing sheet 1 under a die when the prepared leaf is used and may allow the highly finished sheet to smooth the metal much as the moving flat-iron smooths cloth. If an intimate coherence were provided for minute ruptures of the applied gold would take place when the backing sheet was distorted by the die for it must be borne in mind that the dimensions of the materials treated are so minute that causes apparently insignificant may have a controlling effect on the result.

In Figs. 4 and 5 I have shown diagrammatically a method of producing designs on surfaces which utilizes the improved article already described. In these figures I have chosen for illustration a small book 5 such as is carried in the pocket and the design there-

on is in the form of letters. In carrying out my method the article to be marked such as the book 5 is preferably treated at the general location of the proposed design with a suitable substance or mordant, for instance a preparation of albumen, which is adapted to develop adhesive properties under the local action of a heated die. Over the book is placed a sheet of my improved form of mounted gold leaf with the leaf 4 in contact with the surface to be marked. Pressure is then applied to the assemblage by means of the suitably heated die 6 and preferably part of the surface to be ornamented and part of the mounted 4 leaf are offset from the rest along the lines of the proposed design. The action of the heated die will develop the adhesive properties of the mordant on the surface of the book 5 and also will tend to relax the holding properties of the wax 3. Whatever the action may be, however, it is found that the gold at the location of the design on the die will adhere to the book 5 and that the sheet 1 with the remainder of the gold leaf 4 may be easily stripped from the book leaving the same marked as shown in Fig. 5. The remainder of the leaf 4 is available for further use or, if too small an amount of it is left, it may be readily recovered without dissipation or waste.

The importance of my invention lies in the fact that the quality of the work is in no way diminished even although a backing sheet is used in connection with the gold leaf. The reason for this lies in the use of the backing or carrier for the gold leaf which is in itself adapted to transmit an even, burnishing pressure thereto. The paper, because of the homogeneous consistency thereof and the high finish of its surface, does not in any way roughen the surface of the applied gold when pressed thereagainst and so does not diminish its luster, whereas if ordinary paper were used any inequality or roughness of the surface or screen marks and the pattern or grain of the fibers of the substance of the paper itself would be transferred to the metal as an impression even were the faces of the dies perfectly smooth. In the present case it acts as a perfect impressing surface and the results are as good or superior to those obtained when the metal die is applied directly to the gold leaf itself. It will be apparent that when the die 6 is pressed upon the assemblage that the type 7 will offset part of the surface of the book cover 5 from the rest and a corresponding portion of the gold leaf and its backing sheet and that there is therefore probably a certain relative movement of the various layers so offset. The amount of this movement would be, of course, very slight in any ordinary sense but in view of the delicacy of the materials handled quite

large relatively. If such a movement took place the smooth surface of the sheet 1, which is not in any way disturbed by the pressure thereagainst of constituent fibers of 5 palpable size in the interior part of the sheet, would have only a rubbing or polishing action on the surface of the gold leaf 4 where it appears on the marked article. If ordinary paper were used for the backing then 10 the result of any such rubbing action would be to spoil the luster of the gold but the very smooth and even surface of the backing which I use, especially when lubricated by the thin coating of wax 3, slides readily over 15 the surface of the gold and burnishes or polishes it in the same operation by which it is attached. It should be noted that throughout the operation the gold leaf itself is not subjected to any treatment adversely 20 affecting its character. It is held superficially on top of the backing 3 and is preferably transferred and fastened by the developed adhesiveness of the mordant preliminarily placed on the surface of the book cover 25 5 which long experience in applying ordinary gold leaf has proved the best method. My invention is therefore distinguished from those in which the mordant has been combined with the leaf as by spraying it on the 30 leaf which had been applied to paper. The mordant or adhesive in such cases renders the exposed surface unfit for the amalgamation or welding on of more leaf as explained above and also destroys the luster, giving the 35 metal a somewhat frosted appearance.

In my improved form of mounted leaf the metal is not changed in any way and the highly planished and homogeneous backing supplies a perfectly smooth and polished 40 surface to impress the gold leaf upon the design and the embossed letters therefore have as pure a metallic luster as would be the case were a metallic tool directly in contact with the leaf and the results may be 45 even better than those ordinarily obtained when new tools are used since new tools of the requisite smoothness and polish are not easily to be had.

In the drawings the method of applying 50 the gold to the article to be decorated is shown diagrammatically. It may be practised by hand or by the aid of a suitable machine, such for example as that shown in my Patent No. 1,128,225, February 9, 55 1915, and the sheet of a mounted gold leaf may of course take the form of a roll if so desired.

By the practice of my invention it is possible for unskilled persons to apply the 60 very delicate gold leaf and to handle it by machinery with great facility but at the same time no concessions to ease of operation have been made at the expense of the quality of the work. On the contrary the 65 quality of the finished product has been

given prior consideration and the use of the sheet 1 is not important as a backing only for I am aware that it has been proposed before to mount gold leaf on a backing sheet which would be used in applying 70 it but it has an important function as a co-operating element of the decorating apparatus as it supplies the smooth and uniform surface which presses the gold against the surface to be marked and which therefore allows the true metallic luster of the same to appear on the finished product. Furthermore, as has been explained the smooth and lubricated surface acts as a positive burnishing or polishing element and 80 insures a brilliant appearance of the applied metal.

In the description above I have for convenience referred specifically to gold leaf but it will be understood that I have used 85 those words in an exemplary sense only and that my invention is applicable to various sorts of tenuous lamellæ or "leaves" which have a metallic luster.

What I claim and desire to secure by 90 Letters Patent is:

1. The method of ornamenting surfaces comprising applying to the surface metallic leaf superficially adhering to a backing sheet of homogeneous nature substantially without palpable fiber or grain throughout its substance and having a surface of great smoothness, applying pressure to the assemblage where a transfer of the leaf to the surface to be marked is desired, whereby 95 simultaneously both to cause such transfer and to burnish the transferred metal.

2. The method of ornamenting surfaces comprising applying to the surface metallic leaf superficially adhering to a backing sheet 105 substantially without palpable irregularities both throughout its substance and superficially offsetting the surface and therewith the applied leaf and backing by pressure at the location of the proposed design whereby to cause the transfer of the leaf to the surface to be marked and simultaneously to 110 burnish the transferred metal.

3. The method of ornamenting surfaces comprising assembling with the surface 115 metallic leaf and a flexible burnishing sheet disposed in serial relation as named and applying pressure to the assemblage where a transfer of the leaf to the surface is desired.

4. The method of producing designs on surfaces comprising assembling with the surface metallic leaf and a flexible burnishing sheet disposed in serial relation as named and locally offsetting the assemblage by 125 pressure applied at the lines of the proposed design.

5. The method of ornamenting surfaces comprising applying to the surface metallic leaf superficially adhered by means of a 130

- lubricative adhesive to a flexible backing sheet which has a surface of great smoothness and applying pressure to the assemblage at the location of the proposed design.
6. The method of producing designs on surfaces comprising applying to the surface metallic leaf superficially adhered by means of a lubricative adhesive to a flexible 10 backing sheet of substantially amorphous texture or consistency and having a surface of great smoothness and locally offsetting the assemblage by pressure applied at the location of the proposed design.
- 15 7. The method of ornamenting surfaces comprising applying to the surface metallic leaf mounted on a backing sheet of paper of the characteristics associated with the identifying names "glassine" and "onion-skin" 20 paper by a superficial intervening layer of wax and applying localized pressure to the assemblage by means of a heated die of desired form.
8. The step in the process of marking 25 articles with dies consisting in interposing between the face of the embossing dies and the work upon which they are to be impressed, a subsurface consisting of a flexible sheet of substantially amorphous texture or 30 consistency with a highly planished surface.
9. As a new article of manufacture a flexible backing sheet of substantially amorphous texture or consistency and having a very smooth surface and a metallic leaf superficially adhering to said surface. 35
10. As a new article of manufacture a backing member of thin paper substantially without palpable irregularities both throughout its substance and superficially, and a metallic leaf superficially adhering to 40 said surface.
11. As a new article of manufacture a flexible backing comprising hydrolyzed and coalescent cellulose fibers combined to form a sheet of homogeneous texture or 45 consistency and having a surface of great smoothness and metallic leaf superficially adhering thereto.
12. The method of decorating surfaces with metallic leaf which comprises backing 50 the leaf with material having a glazed surface toward the leaf and impressing portions of the leaf upon the surface by means of heat and pressure applied through the backing.
13. The method of decorating surfaces with metallic leaf, which comprises backing the leaf with paper having a glazed surface toward the leaf and impressing portions of the leaf upon the surface by means of 60 heat and pressure applied through the backing.

In testimony whereof, I have signed my name to this specification.

WILLIAM E. CHOATE.
